UNITED STATES PATENT OFFICE.

GEORGE WILSON, OF ALGONA, IOWA.

BASE-LOCK FOR RECIPROCATING ENGINES.

1,328,110.

Specification of Letters Patent.

Patented Jan. 13, 1920.

Application filed April 3, 1919. Serial No. 287,264.

To all whom it may concern:

Be it known that I, GEORGE WILSON, a citizen of the United States, residing at Algona, in the county of Kossuth and State 5 of Iowa, have invented certain new and useful Improvements in Base-Locks for Reciprocating Engines; and I do hereby declare the following to be a full, clear, and exact description of the invention, such as 10 will enable others skilled in the art to which it appertains to make and use the same.

My invention relates to base locks for reciprocating engines; and, to this end, it 15 consists of the novel devices and combinations of devices hereinafter described and defined in the claims.

The invention is especially adapted for use in connection with engine-propelled section cars of that type wherein the transmission mechanism includes a driving belt, usually arranged to run over a pulley on the engine shaft and a pulley on the driven axle of the car. In this type of section cars, the driving belt is tightened or loosened, by 25 sliding the engine bodily back and forth on a sub-base secured to the platform of the car. The engine is held in different set positions on the sub-base, by means of a hand lever having a pawl arranged for co-operation 30 with a notched quadrant, said lever being fulcrumed on the platform and connected to the engine. This method of holding the engine against the pull of the belt is objectionable, for the reason that it holds 35 against end thrusts in one direction only, thus permitting the engine to work back and forth on its sub-base, under the action of the vibration produced by the piston and connecting rod, and thereby subjects the 40 ways or guides for the engine on the sub-base to great wear. It also subjects the pawl and cooperating teeth on the quadrant to like wear under the pull of the belt. The primary object of my invention is to overcome these objections by providing a positive lock to secure the engine on its sub-base, in different set positions, as will hereinafter appear.

In the accompanying drawings, which 50 illustrate the invention, like characters indicate like parts throughout the several views.

Referring to the drawings:—

Figure 1 is a side elevation of an engine-propelled section car having the invention 55 incorporated therein;

Fig. 2 is a fragmentary view partly in side elevation and partly in longitudinal vertical section, on an enlarged scale;

Fig. 3 is a view principally in rear end elevation, with some parts sectioned on the line 3—3 of Fig. 2;

Fig. 4 is a fragmentary plan view with some parts sectioned on the line 4—4 of Fig. 2;

Fig. 5 is a perspective view of the anchor plate; and

Fig. 6 is a fragmentary view, partly in elevation and partly in longitudinal vertical section showing a slight modification of the means for operating the locking device. 70

Of the parts of the section car illustrated, it is important to note the platform 7, and front and rear axles 8, to which are secured pairs of wheels 9, arranged to run on a track 10. The section car is propelled by 75 an internal combustion engine of the horizontal type, and is indicated as an entirety by the numeral 11. Keyed to the engine shaft, is a relatively small pulley 12, and rigidly secured to the rear or driven axle 80 8, is a relatively large pulley 13, and over which two pulleys runs a belt 14.

Cast with the crank case of the engine 11, is a base in the form of a pair of laterally spaced flanges 15, which slidably rest upon 85 a sub-base 16, having longitudinal ways 17 with which the flanges 15 closely engage to guide the engine with freedom for straight line sliding movement parallel to the belt 14. The platform under the sub-base 16 is 90 cut away at 18, and said base is provided at its two rear corners with integrally formed lugs 19, which rest on the platform 7, and are rigidly secured thereto by nut-equipped bolts 20. A transverse bar 21 is 95 rigidly bolted to the platform 7, just forward of the sub-base 16, and the adjacent end of said sub-base is secured thereto, at its transverse center, by a horizontal pivot pin 22. Obviously, the connections 20 and 100 22 afford a three-point support for the sub-base 16 on the platform 7, and thereby permit said sub-base to remain level, irrespective of the twisting movement of the platform 7. 105

The engine 11 is moved either forward or backward on the sub-base 16 by a hand lever 23, the lower end of which is fulcrumed on a bearing bracket 24 bolted to the platform 7, rearward of said sub-base, and is inter- 110

2
mediately pivoted by a link 25 to the crank case of said engine. To positively lock the engine 11 to the sub-base 16, against movement in either direction with respect to the travel of the belt 14, there is provided a horizontally disposed anchor plate 26 and an overlying substantially parallel anchor bar 27, said plate and bar having cut in the opposing faces of their outer or free ends a plurality of interlocking transverse teeth or lock lugs 28. The faces of the teeth 28, as shown, are flat and extend at right angles to the anchor plate and bar with which they are formed. The inner end of the anchor plate 26 is rigidly bolted to the upper face of the sub-base 16 and the anchor bar 27 is intermediately pivoted at 29 to the underside of the crank case of the engine 11.

A depending stem 30 is rigidly secured to the long or free end of the anchor bar 27 with its body portion extending through a longitudinal slot 31 in the anchor plate 26, said slot being open at its outer end. The lower end of the stem 30 is screw-threaded to receive a nut 32, which supports a washer 33. A coiled spring 34 is compressed between the under face of the anchor bar 26 and the washer 33 and yieldingly draws the anchor bar 27 toward said plate with the teeth 28 interlocked. To swing the anchor bar 27 on its pivot 29, and thereby disengage its teeth 28 from the teeth of the anchor plate 26, there is provided, as shown in Figs. 1 to 4, inclusive, for coöperation with the hand piece of the lever 23, a hand piece 35 attached by short links 36 to said lever and connected by a rod 37 to the free end of said anchor bar.

It will be noted that the anchor bar 27, owing to its length, must swing through a considerable arc to disengage its teeth 28 from the teeth of the anchor plate 26, and hence, a considerable movement of the hand piece 35 is required to release said anchor bar from the anchor plate. This feature is not objectionable, but it is awkward, when there is a relatively large number of teeth 28 on the anchor bar 27. To reduce the movement of the hand piece 35, and, at the same time, impart the required lifting movement of the anchor bar 27 from the anchor plate 26, there is provided, as shown in the modification, illustrated in Fig. 6, a relatively long arm 38 to the free end of which the rod 37 is pivoted. The inner end of the arm 38 is pivoted at 39 to the inner end of the anchor plate 26 and its free or outer end underlies a laterally projecting pin 40 attached to the anchor bar 27.

60 To secure the engine 11 within its ways or guides 17, with freedom for sliding movement imparted thereto by the lever 23 and link 25, longitudinally extended lock bars 41 are suspended under the sub-base 16 from the engine base or flanges 15 by nut-

equipped stubs 42. These stubs 42 are secured to the lock bars 41 and project upward through long slots 43 in the sub-base 16 and bores in the flanges 15, and their nuts rest upon the upper faces of said flanges 70 and support the lock bars therefrom. Obviously, the lock bars 41 must have sufficient play to permit the engine to freely slide on its sub-base. To take up this play and frictionally clamp the engine on its sub-base against vertical vibratory movement produced by the engine and the movement of the car on the rails and also to automatically take up wear between the engine and sub-base, there is attached to the short end 80 of the anchor bar 27 a clamping head 44. This clamping head 44, as shown, is in the form of a flat bar, the ends of which underlie the lock bars 41, at their intermediate portions, and are secured thereto by rivets 85 or otherwise.

A nut-equipped bolt 45 adjustably suspends the clamping head 44 at said intermediate portion from the short end of the anchor bar 27 and also permits independent 90 movement of said bar, in respect to the clamping head 44. When the teeth 28 are interlocked, the spring 34, owing to the increased leverage of the long end of the anchor bar 27 over its short end, exerts sufficient force on the head 44 to frictionally clamp the lock bars 41 against the under face of the sub-base 16 and to frictionally clamp the engine onto the upper face 95 thereof.

To slide the engine 11 on the sub-base 16, for the purpose of tightening or loosening the belt 14, the hand piece 35 is first operated to lift the anchor bar 27 and carry its teeth 28 out of interlocking engagement 105 with the teeth on the anchor plate 26. This movement of the anchor bar 27 simultaneously releases the clamping head 44. Then, by manipulating the lever 23, the engine may be slid on the sub-base and positioned to place the belt 14 under the desired tension. After the engine 11 is properly positioned, the hand piece 35 is released to permit the spring 34 to return the anchor bar 27 to normal position and again interlock 110 its teeth with the teeth on the anchor plate 26. This movement of the anchor bar 27 again carries the clamping head 44 into position to frictionally clamp the engine on the sub-base. With the parts thus positioned, the engine is securely held on its sub-base against the action of the pull of the belt and vibratory movement produced by the engine and the movement of the car on the track.

125 What I claim is:—

1. The combination with the platform and wheels of a car, of a sub-base having a three-point support from said platform, a reciprocating engine adjustably mounted on 130

- the sub-base, and a transmission mechanism for driving certain of said wheels from the engine.
2. The combination with the platform and 5 wheels of a car, of a sub-base having one of its ends rigidly secured to said platform and having its other end secured thereto in a horizontal pivot, a reciprocating engine adjustably mounted on the sub-base, and 10 transmission mechanism for driving certain of said wheels from the engine.
3. The combination with the platform and 15 wheels of a car, of a sub-base having one of its ends rigidly secured to said platform, a transverse bar rigidly secured to said platform at the other end of the sub-base, a horizontal pivot connecting the intermediate portion of the adjacent end of the sub-base to said bar, and a reciprocating engine ad- 20 justably mounted on the sub-base, and a transmission mechanism for driving certain of said wheels from the engine.
4. The combination with the platform and 25 wheels of a car, of a reciprocating engine mounted on said platform, transmission mechanism including a belt, for driving certain of said wheels from the engine, said engine being adjustable on said platform to tighten or loosen the belt, a positive lock for 30 securing the engine to the platform against movement in either direction in respect to the travel of said belt, and an automatic take-up device to prevent vertical play of the engine in respect to the platform.
5. The combination with the platform and 35 wheels of a car, of a reciprocating engine mounted on the platform, transmission mechanism including a belt, for driving certain of said wheels from the engine, said engine being adjustable on the platform to tighten or loosen the belt, a positive lock for 40 securing the engine to the platform against movement in either direction in respect to the travel of said belt, and yielding clamping 45 means for securing the engine against vertical movement in respect to said platform.
6. The combination with the platform and 50 wheels of a car, of a reciprocating engine mounted on said platform, transmission mechanism, including a belt for driving certain of said wheels from the engine, said engine being adjustable on said platform to tighten or 55 loosen the belt, and a combined lock and clamp for positively securing the engine to the platform against movement in either direction in respect to the travel of said belt and for yieldingly holding the same against vertical movement.
7. The combination with the platform and 60 wheels of a car, of a sub-base secured to said platform, a reciprocating engine mounted on the sub-base, said engine being adjustable on said platform to tighten or loosen the belt, means for securing the engine to the 65 sub-base, transmission mechanism, includ- ing a belt, for driving certain of said wheels from the engine, and means for clamping the engine to the sub-base.
8. The combination with the platform and 70 wheels of a car, of a sub-base secured to said platform, a reciprocating engine mounted on the sub-base, said engine being adjustable on said platform to tighten or loosen the belt, means for securing the engine to the sub-base, transmission mechanism, in- 75 cluding a belt for driving certain of said wheels from the engine, and yielding means for clamping the engine to the sub-base.
9. The combination with the platform and 80 wheels of a car, of a sub-base secured to said platform, a reciprocating engine mounted on the sub-base, transmission mechanism, in- 85 cluding a belt, for driving certain of said wheels from the engine, said engine being adjustable on said platform to tighten or loosen the belt, an anchor plate on the sub-base, and an anchor bar pivoted to the engine and having interlocking toothed engagement with the anchor plate for positively holding the engine against movement 90 on the sub-base in either direction in respect to the travel of the belt.
10. The combination with the platform and 95 wheels of a car, of a sub-base secured to said platform, a reciprocating engine mounted on the sub-base, transmission mechanism, including a belt, for driving certain of said wheels from the engine, said engine being adjustable on said platform to tighten or loosen the belt, an anchor plate on the sub-base, an anchor bar pivoted to the engine and having interlocking toothed engagement with the anchor plate for positively holding the engine against movement 100 on the sub-base in either direction in respect to the travel of the belt, and yielding means for holding the anchor bar interlocked with the anchor plate.
11. The combination with the platform and 105 wheels of a car, of a sub-base secured to said platform, a reciprocating engine mounted on the sub-base, transmission mechanism, including a belt, for driving certain of said wheels from the engine, said engine being adjustable on said platform to tighten or 110 loosen the belt, an anchor plate on the sub-base, an anchor bar pivoted to the engine and having interlocking toothed engagement with the anchor plate for positively holding the engine against longitudinal 115 movement on the sub-base in either direction, a hand lever, and connections from the lever to the engine and anchor bar for sliding the engine on the sub-base to tighten or loosen the belt, and for releasing the anchor 120 bar from the anchor plate.
12. The combination with the platform and 125 wheels of a car, of a sub-base secured to said platform and having ways, a reciprocating engine mounted on the sub-base be- 130

- 4
- 5   tween said ways, transmission mechanism, including a belt, for driving certain of said wheels from the engine, said engine being adjustable to said platform to tighten or loosen the belt, means including a pair of longitudinally extended lock bars located under the sub-base 60 and having screw threaded studs extending through slots in the sub-base and bores in the engine base, nuts applied to the upper ends of said studs for suspending the lock bars from the engine base, a bar intermediately fulcrumed on the engine and having on its short end a head underlying the lock bars, and means operative on the long end of said bar to clamp the engine and lock bars on the sub-base.
- 10   13. The combination with the platform and wheels of a car, of a sub-base secured to said platform and having ways, a reciprocating engine mounted on the sub-base between said ways, transmission mechanism, including a belt, for driving certain of said wheels from the engine, said engine being adjustable on said platform to tighten or loosen the belt, means including a pair of longitudinally extended lock bars located under the sub-base, for securing the engine between said ways with freedom for sliding movement, a clamping head adjustably secured to the short end of said bar and underlying the lock bars, and means operative on the long end of said bar to clamp the engine and lock bars on the sub-base. 70
- 15   14. The combination with the platform and wheels of a car, of a sub-base secured to said platform and having ways, a reciprocating engine mounted on the sub-base between said ways, transmission mechanism, including a belt, for driving certain of said wheels from the engine, said engine being adjustable on said platform to tighten or loosen the belt, means including a pair of longitudinally extended lock bars located under the sub-base, for securing the engine between said ways with freedom for sliding movement, a clamping head adjustably secured to the short end of said bar and underlying the lock bars, and means operative on the long end of said bar to clamp the engine and lock bars on the sub-base. 75
- 20   15. The combination with the platform and wheels of a car, of a sub-base secured to said platform and having ways, a reciprocating engine mounted on the sub-base between said ways, transmission mechanism, including a belt, for driving certain of said wheels from the engine, said engine being adjustable on said platform to tighten or loosen the belt, means including a pair of longitudinally extended lock bars located under the sub-base, for securing the engine between said ways with freedom for sliding movement, a clamping head adjustably secured to the short end of said bar and underlying the lock bars, and means operative on the long end of said bar to clamp the engine and lock bars on the sub-base. 80
- 25   16. The combination with the platform and wheels of a car, of a sub-base secured to said platform, a reciprocating engine mounted on the sub-base, transmission mechanism, including a belt, for driving certain of said wheels from the engine, said engine being adjustable on said platform to tighten or loosen the belt, an anchor plate on the sub-base, an anchor bar pivoted to the engine and having interlocking toothed engagement 85 with the anchor plate for positively holding the engine against movement on the sub-base in either direction, in respect to the travel of the belt, a depending stem secured to the anchor bar with its body portion extending through a slot in the anchor plate and having on its lower end a nut, and a coiled spring compressed between said anchor plate and nut. 90
- 30   17. The combination with the platform and wheels of a car, of a sub-base secured to said platform, a reciprocating engine mounted on the sub-base, transmission mechanism, including a belt, for driving certain of said wheels from the engine, said engine being adjustable on said platform to tighten or loosen the belt, an anchor plate on the sub-base, an anchor bar pivoted to the engine and having interlocking toothed engagement with the anchor plate for positively holding the engine against longitudinal movement on the sub-base in either direction in respect to the travel of the belt, an arm pivoted in respect to the anchor plate, a pin on the anchor bar overlying the free end of 95 said arm, a hand lever, and connections from the lever to the engine and arm for sliding the engine on the sub-base and for releasing the anchor bar from the anchor plate. 100
- 35   18. The combination with the platform and wheels of a car, of a sub-base secured to said platform and having ways, a reciprocating engine mounted on the sub-base between said ways, transmission mechanism, including a belt, for driving certain of said wheels from the engine, said engine being adjustable on said platform to tighten or loosen the belt, means including a pair of longitudinally extended lock bars located under the sub-base, for securing the engine between said ways with freedom for sliding movement, a clamping head adjustably secured to the short end of said bar with freedom for limited movement in respect thereto, and underlying the lock bars, and means operative on the long end of said bar to clamp the engine and lock bars on the sub-base. 105
- 40   19. The combination with the platform and wheels of a car, of a sub-base secured to said platform and having ways, a reciprocating engine mounted on the sub-base between said ways, transmission mechanism, including a belt, for driving certain of said wheels from the engine, said engine being adjustable on said platform to tighten or loosen the belt, means including a pair of longitudinally extended lock bars located under the sub-base, for securing the engine between said ways with freedom for sliding movement, a clamping head adjustably secured to the short end of said bar with freedom for limited movement in respect thereto, and underlying the lock bars, and means operative on the long end of said bar to clamp the engine and lock bars on the sub-base. 110
- 45   20. The combination with the platform and wheels of a car, of a sub-base secured to said platform and having ways, a reciprocating engine mounted on the sub-base between said ways, transmission mechanism, including a belt, for driving certain of said wheels from the engine, said engine being adjustable on said platform to tighten or loosen the belt, means including a pair of longitudinally extended lock bars located under the sub-base, for securing the engine between said ways with freedom for sliding movement, a clamping head adjustably secured to the short end of said bar with freedom for limited movement in respect thereto, and underlying the lock bars, and means operative on the long end of said bar to clamp the engine and lock bars on the sub-base.
- 50   21. The combination with the platform and wheels of a car, of a sub-base secured to said platform and having ways, a reciprocating engine mounted on the sub-base between said ways, transmission mechanism, including a belt, for driving certain of said wheels from the engine, said engine being adjustable on said platform to tighten or loosen the belt, means including a pair of longitudinally extended lock bars located under the sub-base, for securing the engine between said ways with freedom for sliding movement, a clamping head adjustably secured to the short end of said bar with freedom for limited movement in respect thereto, and underlying the lock bars, and means operative on the long end of said bar to clamp the engine and lock bars on the sub-base.
- 55   22. The combination with the platform and wheels of a car, of a sub-base secured to said platform and having ways, a reciprocating engine mounted on the sub-base between said ways, transmission mechanism, including a belt, for driving certain of said wheels from the engine, said engine being adjustable on said platform to tighten or loosen the belt, means including a pair of longitudinally extended lock bars located under the sub-base, for securing the engine between said ways with freedom for sliding movement, a clamping head adjustably secured to the short end of said bar with freedom for limited movement in respect thereto, and underlying the lock bars, and means operative on the long end of said bar to clamp the engine and lock bars on the sub-base.

In testimony whereof I affix my signature. 110

GEORGE WILSON.
